WILLIAM R. CUTHBERT AND EARL W. SODEBERG, OF FORT MADISON, IOWA, ASSIGNEES
TO W. A. SHEAFFER PEN CO., OF FORT MADISON, IOWA, A CORPORATION OF DELA-
WARE

DESIGN FOR A MECHANICAL PENCIL

Application filed August 30, 1929. Serial No. 32,633. Term of patent 14 years.

To all whom it may concern:

Be it known that we, WILLIAM R. CUTHBERT and EARL W. SODEBERG, citizens of the United States, residing at Fort Madison, in the county of Lee and State of Iowa, have invented a new, original, and ornamental Design for a Mechanical Pencil, of which the following is a specification, reference being had to the accompanying drawing forming a part thereof.

The figure shows a front elevational view of a mechanical pencil illustrating our new design.

We claim:

The ornamental design for a mechanical pencil substantially as shown.

WILLIAM R. CUTHBERT.
EARL W. SODEBERG.
